PUMPING APPARATUS

Otto Staerker, Gladewater, Tex.

Application January 17, 1938, Serial No. 185,295

15 Claims.

(Cl. 103—1)

This invention relates to new and useful improvements in pumping apparatus.

One object of the invention is to provide an improved pumping apparatus for efficiently lifting fluids from deep wells or shafts to the surface and being particularly adapted for use in the pumping of oil wells.

An important object of the invention is to provide an improved pumping apparatus having a pair of pump plungers, one of which is operated by the usual pump rods, while the second is actuated by the pressure of the fluid being pumped, whereby a greater or increased volume of fluid may be lifted without increasing the pumping stroke and without materially increasing the load on the pump rods.

Another object of the invention is to provide an improved pumping apparatus wherein an auxiliary pump plunger is located below the usual reciprocating plunger and has its lower end exposed to the bottom hole pressure, or pressure of the well fluid, whereby said auxiliary plunger is reciprocated by the differential in pressures above and below the same; the construction of the apparatus being such that the operation of the usual pump plunger results in setting up a sufficient pressure differential across the auxiliary plunger to permit movement thereof, whereby the usual pump plunger controls the operation of the auxiliary plunger so that both plungers operate at the same time to lift the well fluid.

A further object of the invention is to provide an apparatus of the character described wherein two fluid chambers, each of which communicates with the well tubing, are employed, with a pump plunger for each chamber for raising the fluid therefrom into the tubing; the lower plunger having means for permitting a flow therethrough into the chamber of the upper plunger upon the downstroke, whereby said upper chamber is supplied with fluid to be lifted; there also being means for by-passing fluid around the lower plunger to its fluid chamber when said lower plunger reaches the top of its stroke, whereby both chambers are supplied with fluid upon each stroke of the plungers so that upon the next successive stroke, said fluid may be lifted.

Still another object of the invention is to provide an auxiliary pump plunger in a pumping apparatus which is actuated by the pressure differential above and below the same and having a bore for permitting flow therethrough, with a check valve for controlling said flow and normally actuated by the pressure differential thereacross; there being positive means for closing

the check valve when the plunger reaches the end of its downstroke, whereby fluid is trapped above the plunger.

A particular object of the invention is to provide an improved apparatus of the character described, wherein the working barrels may be connected to and lowered with the well tubing, after which the plunger assembly may be lowered into the working barrels, whereby the plunger assembly may be removed or replaced within the working barrels without disturbing the working barrels or the well tubing to which said barrels are connected.

A still further object of the invention is to construct the pump plungers in such manner that the pump rods may be connected thereto or disconnected therefrom from the well surface, whereby said rods may be run into the well separately from the well tubing and pump assembly.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a view, partly in elevation and partly in section, of a pumping apparatus, constructed in accordance with the invention, and mounted in a well casing.

Figure 2 is an enlarged, transverse, vertical, sectional view of the upper portion of the apparatus.

Figure 3 is a similar view of the lower portion of the apparatus.

Figure 4 is a partial, sectional view of the upper portion of the auxiliary plunger in its raised position.

Figure 5 is a horizontal, cross-sectional view, taken on the line 5—5 of Figure 2.

Figure 6 is a horizontal, cross-sectional view, taken on the line 6—6 of Figure 3.

Figure 7 is a horizontal, cross-sectional view, taken on the line 7—7 of Figure 3.

Figure 8 is a transverse, vertical, sectional view of a modified form of the invention, and

Figure 9 is a transverse, vertical, sectional view of still another form of the invention.

This sole application is filed as a continuation-in-part of the abandoned joint application of Otto Staerker and Ben H. Ravenelli, Serial No. 139,872, filed April 30, 1937; the invention set forth herein having been disclaimed by the latter.

In the drawings, the numeral 10 designates a

well casing which has the usual casing head 11 at its upper end. The well tubing 12 extends axially through the casing and its upper end projects from the casing head. This projecting end of the tubing has the usual flow connections and controls mounted therein. In wells where pumping, or other auxiliary fluid lifting methods, are employed, the well fluid stands at a level in the casing and tubing and the elevation of such level is dependent upon the particular conditions of the well. In Figure 1, the standing liquid is designated at L, but it is manifest that the level will vary on each well.

A swaged nipple 13 is screwed onto the lower end of the well tubing and a pipe section 14, which has a larger diameter than the tubing, has its upper portion connected to the nipple, whereby said pipe section depends from the tubing. A sleeve or elongate coupling member 15 is threaded onto the lower end of the section 14, while its lower end receives the upper end of a lower pipe section 16, which is of substantially the same diameter as the upper pipe 14. The usual perforated sleeve or well screen 17 depends from the pipe 16, being secured thereto by a coupling collar 18. Thus, it will be seen that the assembly, which houses the pumping apparatus, includes the two pipe sections 14 and 16 which are connected by the coupling sleeve 15, said assembly being mounted on the lower end of the well tubing and being preferably submerged below the liquid level L in the well bore.

An upper working barrel A is mounted axially within the upper pipe section 14 and has its lower end threaded into a collar 19 which extends upwardly from a transverse partition 20 located within the coupling sleeve 15. The partition is preferably integral with the sleeve and extends laterally from one wall thereof. The partition terminates short of the opposite wall and is provided with an opening 21 located axially of the sleeve. The working barrel extends upwardly from the collar 19 and has its upper end extending through a guide spider 22 which holds the barrel in axial alignment with the pipe 14. The extreme upper end of the barrel terminates short of the well tubing 12, whereby a flow from the pipe section 14 into the tubing is permitted.

A standing valve 23 is mounted in the lower end of the working barrel A and includes a seat 24, ball 25 and cage 26. The cage and seat are carried by a supporting sleeve 27 which has its lower end screwed into a collar 28 and said collar is suitably secured within the opening 21 of the partition 20 with the coupling 15. Packing rings 29 surround the supporting sleeve and engage the bore of the working barrel to pack off between these parts and manifestly, a flow from below the partition 20 flowing through the opening 21 therein, must pass upwardly through the supporting sleeve 27 and unseat the ball 25 in order to enter the working barrel A.

A pump plunger 30 is slideable in the working barrel A above the standing valve 23, being secured to the lower end of the usual pump rods 31 which extend axially through the tubing. The plunger is formed with an axial bore 32 and a valve seat 33 is mounted within the upper end of the bore. A valve cage 34 is secured to the upper end of the plunger and a ball valve 35 is confined within said cage and constitutes the usual traveling valve. When the pump rods 31 are reciprocated, the plunger 30 is reciprocated within the working barrel to lift the fluid from below the standing valve upwardly into the tub-

ing. The rods 31 may be operated by any suitable means (not shown).

As hereinbefore stated, the transverse partition 20 within the sleeve 15 has one edge terminating short of the sleeve and an arcuate depending wall 36 extends vertically from the partition. This wall is offset laterally at 37 (Figure 2) and then extended downwardly to form an arcuate skirt 38. A collar 39 is formed at the lower end of the skirt and with such arrangement, it will be obvious that the interior of the coupling sleeve 15 is divided into two substantially vertical passages or chambers A' and B'. The passage A' has its lower end communicating with the interior of the lower pipe section 16 while its upper end communicates with the interior of the working barrel A, through the standing valve 25. The passage or chamber B' has its upper end communicating with the interior of the upper pipe section 14, such interior being the annular space between the pipe and the working barrel A.

The lower end of the passage B' communicates with a lower working barrel B which has its upper end threaded into the collar 39 and which extends axially through the pipe section 16. The lower end of the barrel is held in axial alignment with the section 16 by a spider or guide member 16'. A standing valve 40, which is similar in construction to the valve 23, is mounted within the upper end of the barrel B and this valve includes a seat 41, ball 42 and cage 43, as well as a supporting sleeve 44 and packing cups 45. The valve 40 acts as a check valve, being unseated by fluid pressure from below and seated by fluid pressure from above. Of course, said valve will seat by gravity if the pressures thereacross are equalized. From the foregoing, it will be seen that fluid from the lower pipe section 16 may flow upwardly through the passage A' in the sleeve 15 and may then enter the working barrel A, from where it may be lifted into the tubing 12. Fluid from the lower working barrel B may flow upwardly past the valve 40 into the passage B' and then into the pipe section 14, from where it may enter the tubing around the upper end of the upper working barrel A.

For lifting the fluid within the lower working barrel B, a lower pump plunger 50 is mounted to reciprocate in said barrel. The plunger is tubular and is provided with packing cups 51 on its exterior. A valve seat 52 is located at the upper end of the plunger and is adapted to be engaged by a ball 53 which is confined within a cage 54. The valve forms a traveling valve which moves with the plunger.

The lower end of the plunger is connected, by a coupling collar 55, with a tubular mandrel 56 which extends from the lower open end of the working barrel B. The lower end of the mandrel is threaded into a swaged nipple 57 which is, in turn, carried by the upper end of a tubular piston 58. The piston is slideable within the pipe section 16 and has a plurality of packing rings 59 confined thereon and these rings engage the wall of the pipe 16 to pack off between said pipe and the piston. A valve seat 60 is mounted at the lower end of the piston and is held in place by a valve cage 61 which is screwed onto the lower end of the piston. A ball 62 is confined within the cage and is adapted to engage the seat to close the bore 58' of the piston.

When the ball is unseated, it falls onto the concaved head 65 of an operating stem 66, which stem is slidably engaged within an axial opening

67 in the cage 61. The lower end of the stem extends into a metallic flanged cup 68. A transverse spider 69 is mounted between the ends of the pipe section 16 and well screen 17 and has an axial opening therein. The opening is surrounded by an upstanding collar 70 and a coiled spring 71 is confined between the spider and the cup 68, exerting its pressure to urge the cup upwardly at all times. As shown in Figure 3, the spring is fully expanded and the piston 58 is raised with the stem 66 clear of the bottom of the cup. When the piston is lowered, the stem strikes the bottom of the cup and the head 65 is moved into engagement with the ball 62 to hold the same seated, as will be explained.

When the ball is unseated, fluid from below the piston may flow through the bore 58' and into the mandrel 56, from where it may flow through the lower pump plunger 50 and into the working barrel B above said plunger. From the working barrel the fluid may pass into the passage B' and then to the pipe section 14, as has been explained.

A portion of the fluid which flows upwardly through the bore 58' of the piston 58, when the ball 62 is unseated, passes outwardly through radial ports 63 which are located in the swaged nipple 57 (Figure 7). The nipple is below the mandrel 56 and the fluid flowing through the ports 63 enters the pipe section 16 above the piston 58. This fluid flows upwardly through the pipe 16 around the working barrel B and enters the passage A' within the coupling sleeve 15, from where it passes into the upper working barrel A and then is lifted into the tubing.

During the upper stroke of the piston 58, the valve 62 is closed as will be explained, and fluid from below the piston cannot flow upwardly through the bore 58' thereof. When the piston reaches the top of its stroke, the fluid thereabove has been lifted and to equalize the pressure above and below the piston 58, radial by-pass openings or ports 72 and 73 are provided in the wall of the pipe. The openings are spaced sufficiently far apart so that the packing rings 59 of the piston 58 are located therebetween when the top of the piston stroke is reached. The upstroke of the piston is limited by the nipple 57 striking the lower end of the working barrel B, and this stop assures the piston halting in position with the packing rings between the openings 72 and 73, as clearly shown in Figure 4.

When the packing rings 59 move between the openings 72 and 73, the fluid from below the piston flows through the lower openings 72 and into an annular manifold 74 which is secured to the exterior of the pipe section 16. From the manifold, the fluid flows through the ports 73 and into the pipe 16 above the piston 58. As soon as the piston starts its downward movement the packing rings 59 cover the ports 72 and further flow therethrough is prevented. Upon the start of the downstroke of the piston, the ball 62 is unseated, as will be explained, and the fluid from below the piston flows upwardly through the bore 58' thereof and then through the ports 63 in the swaged nipple 57, as well as upwardly into the mandrel 56.

In operation, assuming the plungers 30 and 50, as well as the piston 58 to be in their lowered positions, it will be obvious that the stem 66 has been engaged by the bottom of the cup 68 and the head 65 of said stem has been moved upwardly by the tension of the spring 71, whereby the ball 62 is held in engagement with its seat

60 to close the bore of the piston 58. Fluid is present within the pipe section 16 above the piston and is also present in the upper section 14, as well as in the working barrels A and B, this 5 fluid having entered these parts upon the previous operation. As the pump rods 31 raise the upper plunger 30, the fluid in the working barrel A above said plunger is lifted. At the same time, a suction is created below the plunger, whereby the ball 25 of the standing valve 23 at the lower end of the upper working barrel A is lifted from its seat. This permits the fluid to be drawn from the passage A' and from the interior of the pipe section 16 above the piston 58. 10 The weight of the fluid column within the well casing 10 or the bottom hole pressure of the well is acting upwardly against the lower end of the piston 58 and this well pressure is more or less constant. When the plunger 30 is raised by the 15 pump rods 31 to draw liquid from the pipe section 16 above the piston 58, the pressure of the fluid above said piston is reduced. This reduction in fluid pressure above the piston 58 permits the bottom hole or well pressure to act upwardly 20 against the piston to lift said piston or move the same upwardly in the pipe section 16. As soon as the piston is moved sufficiently to disengage the stem 66 from the cup 68, the head 65 falls away from the ball 62. However, since the pressure 25 below the piston 58 is greater than the pressure thereabove, this greater pressure acts through the valve cage 61 against the ball 62 to hold the same in its seated position upon upward movement of the piston. 30 Upward movement of the piston 58 by the well pressure causes an upward movement of the lower pump plunger 50, whereby the liquid above the pump plunger 50 within the working barrel B is raised. This upwardly moving fluid unseats 35 the valve 42 and permits the fluid to flow through the passage B' and into the interior of the upper pipe section 14. From the pipe section 14, the fluid travels past the upper end of the working barrel A and enters the tubing 12. Of course, the fluid lifted by the upper plunger 30 is raised 40 directly into the tubing 12.

With such arrangement, upon the upward movement of the plunger 30 by the pump rod, the lower pump plunger 50 is also actuated and therefore an increased amount of fluid is lifted due to the double plunger. The piston 58 continues its upward movement until the swaged nipple 57 at its upper end strikes the lower end of the lower working barrel B, at which time the upward movement of said piston and the plunger 50 attached thereto, is halted. In such position, the packing rings 59 on the exterior of the piston 58 have moved into a position between the by-pass openings 72 and 73. This permits the well fluid below the piston to pass upwardly through the annular space between the piston and the wall of the pipe section 16, whereby such fluid may flow through the openings 72 into the manifold 74. From the manifold the well fluid passes through the openings 73 and into the pipe section 16 above the piston 58. The fluid in this portion of the pipe 16 may flow through the ports 63 in the swaged nipple so as to enter the bore 58' of the piston 58 above the valve 62. Thus, it will be seen that when the piston 58 reaches the upper end of its stroke, the by-pass openings provide means for permitting the well pressure below the piston to flow into the pipe 16 above the piston. Such arrangement permits the pressure on each side of the piston to become equalized and

as soon as such equalization occurs, the piston begins its downward movement due to the weight of the piston and the plunger 50 attached thereto. At the same time that the pressure across the piston 58 is equalized, the pressure on each side of the ball valve 62 is also equalized, whereby said valve may fall by gravity, to its unseated position.

It is pointed out that at the time that the lower piston 58 begins its downward movement, the upper pump plunger 30 has completed its up-stroke and is also beginning its downward movement through the medium of the pump rods 31. This is true because the pressure above the piston 58 cannot equalize until the upper plunger 30 has stopped drawing fluid from the pipe section 16 above the piston. As the piston 58 moves downwardly, the well fluid flows through the cage 61 and past the unseated ball 62. This fluid flows upwardly through the bore 58' of the piston and into the mandrel 56 and plunger 50. The ball 53 is unseated and the fluid enters the working barrel B above the plunger 50. This fluid which enters the barrel B above the valve 53 will not unseat or flow past the valve 42 on the down-stroke, unless the flow of the fluid is sufficient to overcome the back pressure of the column of fluid above the valve 42. A portion of the fluid which is flowing through the bore 58' of the piston, upon the downstroke of said piston, passes through the ports 63 in the swaged nipple 57 and enters the interior of the pipe section 16 above said piston. During the downstroke fluid from the pipe 16 will enter the passage A', from which it will be drawn upon the next succeeding operation. At the same time that the well fluid is being introduced into the passages A' and barrel B, as explained, the upper plunger 30 is moving downwardly within its working barrel A and the fluid which has been drawn into said working barrel upon the upstroke of said plunger, moves upwardly through the plunger and unseats the traveling valve 35, whereby said fluid flows into the upper end of the working barrel A and then into the tubing 12.

As soon as the piston 58 reaches the lower end of its stroke, the stem 66 strikes the spring-pressed cup 68, whereby the head 65 is moved upwardly to raise the ball 62 into contact with its seat 60 to close the bore of the piston 58. The parts remain in this position until the upper plunger 30 is again moved upwardly by the pump rods 31. Such upward movement of the plunger 30 reduces the pressure above the piston 58, as has been explained, thereby permitting the well fluid acting against the bottom of said piston to move the same upwardly to perform the next succeeding operation. With such arrangement, the upper pump plunger 30 is actuated in the usual manner by the pump rod, while the lower pump plunger 50 is actuated by means of the piston 58 which, in turn, is operated by the pressure of the well fluid. It will be evident that a greater amount of fluid may be lifted to the surface upon each operation of the plungers as both plungers are acting to lift fluid to the surface.

In Figure 8, a modified form of the invention is shown, wherein an upper pipe section 80 and a lower pipe section 81 connected by a coupling sleeve 82 is provided. An upper working barrel A1 is located within the upper section 80 while a lower working barrel B1 is mounted within the lower section 81. A passage A2 which communicates with the upper working barrel A1 and also with the interior of the lower section 81 is formed

within the sleeve 82. A similar passage B2 which communicates with the lower working barrel B1 and also with the interior of the upper section 80 is also formed within the coupling 82. An upper pump plunger 83 is secured to the pump rods 31 and is movable within the upper working barrel A1. A lower pump plunger 84 is slidable within the lower working barrel B1 and is connected with the upper pump plunger by a connecting rod 85 and sleeve 85'.

The sleeve 85' is threaded onto the usual pin on the upper end of the plunger and the lower end of the rod which is formed with a head 85a, telescopes said sleeve, the head being slidably confined within the sleeve. The upper and lower ends of the sleeve are formed with relief openings 85b, whereby any fluid which may enter the sleeve is forced therefrom by the head and sliding of the head within the sleeve will not be interfered with. The rod and sleeve form a connection between the pump plungers 83 and 84 and this connection is such that the upper plunger has a longer stroke than the lower plunger. As is clearly shown in Figure 8, initial upward movement of the upper plunger does not impart a movement to the lower plunger as the head 85a of the connecting rod 85 slides through the sleeve 85'. When said head strikes the closed top of the sleeve, continued upward movement of the upper plunger imparts a similar upward movement to the lower plunger. From this point to the top of the stroke the plungers move simultaneously. With the telescoping arrangement between the rod and sleeve, the upper plunger has a longer stroke than the lower plunger and the difference in such strokes is controlled by the length of the sleeves.

In order to permit the well pressure to aid in operating the lower plunger 84, a piston 86 is preferably made integral with the lower end of said lower plunger. The valve cage 61 and ball 62 are mounted on the lower end of the piston 86 and are adapted to close the bore 84' of the lower plunger 84. The head 65, having the depending stem 66, is mounted in the cage 61 and is adapted to engage a ring 87 which is secured to a spring 88. The ring is substituted for the cup 68 in the first form and operates in the same manner. A spider 89 is mounted at the lower end of the pipe section 81 and has a ball check valve 90 mounted therein. This valve is adapted to engage a seat 91 in the spider 89 and acts to prevent a downward flow from the pipe 81, while permitting an upward flow thereby.

The operation of this form is somewhat similar to the first form with the exception that the lower plunger is moved with the upper plunger after the connecting rod head 85a has engaged the top of the sleeve, being aided in its movement by the well pressure. Assuming the plungers to be in their lowered positions, it will be seen that the ball 62 is closed or seated, being held so by the head 65 which has its stem 66 engaged by the ring 87. As the pump rods move upwardly to raise the upper plunger 83, fluid is drawn from the pipe 81 into the passage A2. As soon as the connecting rod head 85a engages the sleeve 85', the lower plunger 84 is raised. Since the piston 86 is a part of the lower plunger 84, said piston moves upwardly therewith and as it does so, the ball 90 is lifted from its seat, whereby the well fluid may enter the pipe section 81 below the piston 86. This pressure acts against said piston to aid in lifting the same. The well fluid is also acting against

the ball 62 to close the bore 84' of the lower plunger 84.

When the plungers 83 and 84 reach the upper end of their stroke, the weight of the fluid within the pipe section 81 above the ball 90 acts downwardly against said ball and causes the same to drop to its seated position. At the same time, the pressure of the liquid column within the pipe section above the piston 86 acts downwardly through ports 92 in the plunger 84 and forces the ball 62 to its unseated position. As the plungers are moved downwardly, the well fluid which has entered the lower end of the pipe section 81 flows upwardly through the bore 84' and unseats the traveling valve of the lower plunger 84. From this point the fluid flows into the passage B2 and upwardly into the upper section 80. A portion of the fluid flowing through the bore 84' of the lower pump plunger 84 passes outwardly through the ports 92 and enters the interior of the pipe section 81 above the piston 86, from which point it flows into the passage A2. Upon the next succeeding operation of the plungers 83 and 84, this fluid is lifted.

In many instances, it is desirable to run the well tubing, having the working barrels attached to its lower end, into the well prior to the running of the pump rods 31. This is advantageous because it is difficult to run the tubing and rods simultaneously. In order to run the tubing and working barrels, as shown in Figure 8 into the well, before the pump rods 31 are connected to the upper plunger 83, the working barrels and pipe sections 80 and 81 are first assembled, with the pump plungers 83 and 84 within their respective working barrels. The rods 31 are not connected with the upper plunger at this time.

The assembly is then connected onto the well tubing and run into the well bore and manifestly, both plungers 83 and 84 fall to their lower-most position. The lower end of the plunger 83 is slotted at 83' to form the usual inlet ports and when the plunger falls to its lowermost position, one of these slots is engaged by a radial lug 92' which extends inwardly into the upper portion of the passage A2.

After the tubing and working barrel assembly has been run into the well, the rods 31 may then be lowered through the tubing. The lower end of the lowermost rod has the usual threaded socket 31' which is adapted to receive the upwardly extending pin 83A on the top of the upper plunger 83. This socket is engaged with the pin and the rods 31 rotated, whereby the pin is screwed into said socket. The plunger 83 and the pin thereon is held against rotation by the engagement of one of the slots 83' with the lug 92' and obviously, the rods 31 may be readily connected to the upper plunger after the tubing and plunger assembly has been lowered into the well. Similarly, the rods may be disconnected from the plunger and removed at any time without disturbing the plunger and working barrel assembly. Thus, the rods 31 and tubing 12 may be run into the well individually.

Since the pump plungers having the traveling valves therein may become worn or for other reasons may necessitate removal from their working barrels, it is desirable that said plungers be removable without disturbing the working barrels and tubing. In Figure 9, a modified form of the invention, wherein the plungers are readily

removable and replaceable within their respective working barrels, is shown.

The structure of this form is similar to that shown in Figure 8 and includes an upper pipe section 100 and lower pipe section 101 connected by a coupling sleeve 102. A suitable standing valve 103 is mounted at the lower end of the lower pipe section 101. The interior of the coupling is divided into two chambers or passages A3 and B3 by an offset partition 104. The lateral portion of the partition is formed with a threaded opening 105 which is adapted to receive a packing element 106, as will be explained. An upper working barrel A4 extends upwardly from the coupling 102 while a lower working barrel B4 has its upper end secured in said coupling, whereby said lower working barrel extends axially through the pipe section 101. It is pointed out that the diameter of the lower working barrel is less than the diameter of the upper barrel and both barrels are axially aligned with the opening 105 in the lateral portion of the partition 104.

The pipe sections 100 and 101, together with the couplings 102 and working barrels A4 and B4 are assembled and lowered with the tubing 12. At the surface an upper plunger 107 and a lower plunger 108 are connected together by a connecting rod 109. The packing element 106 surrounds the rod between the plungers and this element includes a body portion 106' having its external surface threaded. A cap 110 on the packing element confines the packing material around the rod 109 and this cap is formed with a transverse groove 111 in its top, said groove being in cross-section. The depending socket 107' which is provided on the lower end of the plunger 107 and which receives the connecting rod 109, is also angular in cross-section and is adapted to engage the groove 111, as shown in Figure 9.

After the tubing and working barrel assembly has been lowered into the well, the double plunger assembly is connected to the pump rods 31 and is lowered through the tubing 12. The lower plunger 108 passes downwardly through the upper barrel A4, through the opening 105 in the partition 104 and into the lower working barrel B4. The packing element 106 engages the opening 105 and the upper plunger 107 is lowered until the angular socket 107' engages within the groove 111. The pump rods 31 and plunger 107 are then rotated, whereby the packing element is rotated and the body 106' thereof is thus screwed into the opening 105, as shown in Figure 9. After the packing element is in position, the plungers are actuated somewhat similar to the plungers 83 and 84 of Figure 8 to lift the well fluid to the surface except the valve 62 and piston 86 are omitted.

When it is desired to remove the plungers 107 and 108 and the packing element 106, the pump rods 31 and plungers are raised until an angular socket 109' on the lower end of the rod 109 engages within an angular recess 112 formed in the lower end of the body 106' of the packing element 106. Rotation of the rods 31 and plungers will cause the packing element to be unscrewed from the opening 105, after which the plungers may be withdrawn from the working barrels and well tubing.

What I claim and desire to secure by Letters Patent is:

1. A pumping apparatus including, a well tubing, a conductor adapted to be connected in the

well tubing string and having a pair of fluid passages therein, an upper working barrel having communication with one of the passages, a pump plunger operable from the surface of the well movable within said barrel for lifting the fluid from the passage communicating therewith, a lower working barrel communicating with the second passage, a lower pump plunger reciprocable within the lower working barrel for lifting the fluid in the second passage, and a 10 slideable piston connected with the lower plunger for operating the same and having its upper end exposed to the fluid pressure in the first passage which communicates with the upper barrel and having its lower end exposed to the pressure of the well fluid in the well bore, whereby the piston and lower plunger are operated by the pressure differential across the piston.

2. A pumping apparatus including, a well tubing, a conductor adapted to be connected in the well tubing string and having a pair of fluid passages therein, an upper working barrel having communication with one of the passages, a pump plunger operable from the surface of the well movable within said barrel for lifting the fluid from the passage communicating therewith, a lower working barrel communicating with the second passage, a lower pump plunger reciprocable within the lower working barrel for lifting the fluid in the second passage, a slideable piston connected with the lower plunger for operating the same and having its upper end exposed to the fluid pressure in the first passage which communicates with the upper barrel and having its lower end exposed to the pressure of the well fluid in the well bore, whereby the piston and lower plunger are operated by the pressure differential across the piston, said lower plunger having a bore therethrough which communicates with the fluid passages, and means controlling the flow through said bore and arranged to permit a flow through the bore on the downstroke of the plunger and for closing said bore upon the upstroke thereof.

3. A pumping apparatus including, a well tubing, a conductor adapted to be connected in the well tubing string and having a pair of fluid passages therein, an upper working barrel having communication with one of the passages, a pump plunger operable from the surface of the well movable within said barrel for lifting the fluid from the passage communicating therewith, a lower working barrel communicating with the second passage, a lower pump plunger reciprocable within the lower working barrel for lifting the fluid in the second passage, a slideable piston connected with the lower plunger for operating the same and having its upper end exposed to the fluid pressure in the first passage which communicates with the upper barrel and having its lower end exposed to the pressure of the well fluid in the well bore, whereby the piston and lower plunger are operated by the pressure differential across the piston, said piston having a bore communicating with the fluid passages, a valve at the lower end of the piston actuated by the pressure differential thereacross, and means for positively closing said valve when the piston is at the end of its downstroke.

4. A pumping apparatus including, a well tubing, a conductor adapted to be connected in the well tubing string and having a pair of fluid passages therein, an upper working barrel having communication with one of the passages, a pump plunger operable from the surface of the well

movable within said barrel for lifting the fluid from the passage communicating therewith, a lower working barrel communicating with the second passage, a lower pump plunger reciprocable within the lower working barrel for lifting the fluid in the second passage, means for connecting the plungers together so that they move simultaneously, and a piston connected with the lower plunger and exposed to the pressure of the well fluid in the bore, whereby said well fluid pressure aids in lifting the plungers on the upstroke.

5. A pumping apparatus including, a well tubing, a conductor adapted to be connected in the well tubing and having a pair of fluid passages therein, an upper working barrel having communication with one of the passages, a lower working barrel communicating with the second passage, a plunger adapted to reciprocate in each 15 working barrel, a telescoping connection between the plungers whereby one plunger has a longer stroke than the other, and means for reciprocating the plungers from the surface of the well to raise the well fluid.

25 6. A pumping apparatus including, a well tubing, a conductor adapted to be connected in the well tubing and having a pair of fluid passages therein, an upper working barrel having communication with one of the passages, a lower working barrel communicating with the second passage, a plunger adapted to reciprocate in each 30 working barrel, a telescoping connection between the plungers whereby one plunger has a longer stroke than the other, and pump rods 35 adapted to be lowered through the tubing and arranged to be connected to the upper plunger for operating said plungers.

7. A pumping apparatus including, a well tubing, a fluid conductor adapted to be connected in the 40 tubing string and having a well fluid inlet and also having a pair of communicating fluid passages therein, each passage communicating with the well fluid inlet, an upper cylinder communicating with one of the passages, an upper 45 pump plunger movable within the cylinder and operable from the well surface for lifting the fluid from the passage communicating therewith, a lower cylinder communicating with the second passage, and a lower pump plunger movable 50 within the lower cylinder for lifting the fluid in the second passage, the lower plunger having its upper end exposed to the fluid pressure within the passages and its lower end exposed to the well fluid pressure, whereby said plunger is operable by the differential in pressures above and below the plunger.

8. A pumping apparatus including, a well tubing, a fluid conductor adapted to be connected in the well tubing string and having a well fluid inlet and also having a pair of fluid passages 60 therein, each passage communicating with the well fluid inlet, an upper cylinder communicating with one of the passages, an upper pump plunger movable within the cylinder and operable from the well surface for lifting the fluid from the passage communicating therewith, a lower cylinder communicating with the second passage, a lower pump plunger movable within the lower cylinder for lifting the fluid in the second passage, the lower plunger having its upper end exposed to the fluid pressure within the passages and its lower end exposed to the well fluid pressure so as to be operable by the differential in pressures thereabove and therebelow, and means 65 for reducing the pressure above the lower plunger.

er when the upper plunger begins its upward movement, whereby the well pressure below said lower plunger acts to raise the lower plunger simultaneously with the upper plunger.

9. A pumping apparatus including, a well tubing, a fluid conductor adapted to be connected in the well tubing string and having a well fluid inlet and also having a pair of fluid passages therein, each passage communicating with the well fluid inlet, an upper cylinder communicating with one of the passages, an upper pump plunger movable within the cylinder and operable from the well surface for lifting the fluid from the passage communicating therewith, a lower cylinder communicating with the second passage, a lower pump plunger movable within the lower cylinder for lifting the fluid in the second passage, the lower plunger having its upper end exposed to the fluid pressure within the passages and its lower end exposed to the well fluid pressure so as to be operable by the differential in pressures thereabove and therebelow, means for reducing the pressure above the lower plunger when the upper plunger begins its upward movement, whereby the well pressure below said lower plunger acts to raise the lower plunger simultaneously with the upper plunger, and means for equalizing the pressures above and below the lower plunger when the upstroke is completed, whereby the weight of said plunger will return the same to its lower position.

10. A pumping apparatus including, a well tubing, a fluid conductor adapted to be connected in the tubing string and having a well fluid inlet and also having a pair of communicating fluid passages therein, each passage communicating with the well fluid inlet, an upper cylinder communicating with one of the passages, an upper pump plunger movable within the cylinder and operable from the well surface for lifting the fluid from the passage communicating therewith, a lower cylinder communicating with the second passage, a lower pump plunger movable within the lower cylinder for lifting the fluid in the second passage, the lower plunger having its upper end exposed to the fluid pressure within the passages and its lower end exposed to the well fluid pressure, whereby said plunger is operable by the differential in pressure on opposite sides thereof, the lower plunger having a bore therethrough which communicates with the fluid passages, and means controlling the flow through the bore and arranged to permit a flow through said bore on the downstroke of the plunger and for closing the bore upon the upstroke thereof.

11. A pumping apparatus including, a well tubing, a fluid conductor adapted to be connected in the tubing string and having a well fluid inlet and also having a pair of communicating fluid passages therein, each passage communicating with the well fluid inlet, an upper cylinder communicating with one of the passages, an upper pump plunger movable within the cylinder and operable from the well surface for lifting the fluid from the passage communicating therewith, a lower cylinder communicating with the second passage, a lower pump plunger movable within the lower cylinder for lifting the fluid in the second passage, the lower plunger having its upper end exposed to the fluid pressure within the passages and its lower end exposed to the well fluid pressure, whereby said plunger is operable by the differential in pressure on opposite sides thereof, the lower plunger having a bore therethrough which communicates with the fluid

passages, and means actuated by the differential in pressures thereabove and therebelow for controlling the flow through the bore.

12. A pumping apparatus including, a well tubing, a fluid conductor adapted to be connected in the well tubing string and having a well fluid inlet and also having a pair of fluid passages therein, each passage communicating with the well fluid inlet, an upper cylinder communicating with one of the passages, an upper pump plunger movable within the cylinder and operable from the well surface for lifting the fluid from the passage communicating therewith, a lower cylinder communicating with the second passage, a lower pump plunger movable within the lower cylinder for lifting the fluid in the second passage, the lower plunger having its upper end exposed to the fluid pressure within the passages and its lower end exposed to the well fluid pressure so as to be operable by the differential in pressures thereabove and therebelow, said lower plunger having a bore therethrough which communicates with the fluid passages, a valve actuated by the pressure differential thereacross for controlling the flow through the bore, and means for reducing the pressure above the lower plunger and valve when the upper plunger begins its upward movement, whereby the well pressure below the lower plunger may act against the valve to close the same and also whereby said pressure may act against the lower end of the plunger to lift the same.

13. A pumping apparatus including, a well tubing, a fluid conductor adapted to be connected in the well tubing string and having a well fluid inlet and also having a pair of fluid passages therein, each passage communicating with the well fluid inlet, an upper cylinder communicating with one of the passages, an upper pump plunger movable within the cylinder and operable from the well surface for lifting the fluid from the passage communicating therewith, a lower cylinder communicating with the second passage, a lower pump plunger movable within the lower cylinder for lifting the fluid in the second passage, the lower plunger having its upper end exposed to the fluid pressure within the passages and its lower end exposed to the well fluid pressure so as to be operable by the differential in pressures thereabove and therebelow, said lower plunger having a bore therethrough which communicates with the fluid passages, a valve actuated by the pressure differential thereacross for controlling the flow through the bore, means for reducing the pressure above the lower plunger and valve when the upper plunger begins its upward movement, whereby the well pressure below the lower plunger may act against the valve to close the same and also whereby said pressure may act against the lower end of the plunger to lift the same, and means for equalizing the pressures across the valve and lower plunger when the upstroke is completed, whereby the valve may fall to an open position and said plunger may move downwardly by gravity, the opening of said valve permitting fluid to flow through the bore of the plunger upon the downstroke of said plunger.

14. A pumping apparatus including, a well tubing, a fluid conductor adapted to be connected in the well tubing string and having a well fluid inlet and also having a pair of fluid passages therein, each passage communicating with the well fluid inlet, an upper cylinder communicating with one of the passages, an upper pump plunger

movable within the cylinder and operable from the well surface for lifting the fluid from the passage communicating therewith, a lower cylinder communicating with the second passage, a lower pump plunger movable within the lower cylinder for lifting in the second passage, the lower plunger having its upper end exposed to the fluid pressure within the passages and its lower end exposed to the well fluid pressure so as to be operable by the differential in pressures thereabove and therebelow, said lower plunger having a bore therethrough which communicates with the fluid passages, a valve actuated by the pressure differential thereacross for controlling the flow through the bore, means for reducing the pressure above the lower plunger and valve when the upper plunger begins its upward movement, whereby the well pressure below the lower plunger may act against the valve to close the same and also whereby said pressure may act against the lower end of the plunger to lift the same, means for equalizing the pressures across the valve and lower plunger when the upstroke is completed, whereby the valve may fall to an open position and said plunger may move downwardly by gravity, the opening of said valve permitting fluid to flow through the bore of the plunger upon the downstroke of said plunger,

and means for closing the valve when the downstroke of the lower plunger is completed.

15. A pumping apparatus including, a well tubing, a conductor adapted to be connected in the well tubing string and having a pair of fluid passages therein, an upper working barrel having communication with one of the passages, a pump plunger operable from the surface of the well movable within said barrel for lifting the fluid from the passage communicating therewith, a lower working barrel communicating with the second passage, a lower pump plunger reciprocable within the lower working barrel for lifting the fluid in the second passage, a slideable piston connected with the lower plunger for operating the same and having its upper end exposed to the fluid pressure in the first passage which communicates with the upper barrel and having its lower end exposed to the pressure of the well fluid in the well bore, whereby the piston and lower plunger are operated by the pressure differential across the piston, said piston having a bore communicating with the fluid passages, and a valve at the lower end of the piston actuated by the pressure differential thereacross for closing the bore of said piston on the upstroke thereof and arranged to permit a flow through said bore on the downstroke.

OTTO STAERKER.
